UNITED STATES PATENT OFFICE

THEODORE S. HART, OF NEW BRITAIN, AND PHILIP M. BUSH, OF BLOOMFIELD, CONNECTICUT, ASSIGNEES TO THE HART & HUTCHINSON COMPANY, OF NEW BRITAIN, CONNECTICUT, A CORPORATION OF CONNECTICUT

COMBINED RADIATOR AND HUMIDIFIER

Application filed August 27, 1931. Serial No. 559,686.

This invention relates to humidifying apparatus, and more particularly to an apparatus for simultaneously heating and moistening the air in a room or other enclosure to maintain the proper temperature and relative humidity therein.

One object of this invention is to provide an apparatus of the above nature which may be installed in any modern steam, vapor or hot water heating system.

A further object is to provide a humidifying apparatus which may be readily installed in any existing heating system in place of one of the radiators of said system.

A further object is to provide an apparatus of the above nature having a plurality of humidifying units arranged with respect to each other in staggered relationship and above the radiator section of the apparatus, the hot air rising from said radiator section being caused to rapidly and efficiently absorb moisture from said units before being discharged into the room.

A further object is to provide an apparatus of the above nature employing no moving parts such as fans, belts, electric motors, etc., which would be likely to be noisy and easily get out of order.

A further object is to provide an apparatus of the above nature which will be simple in construction, silent in operation, inexpensive to manufacture, easy to install and manipulate, compact, ornamental in appearance, and very efficient and durable in use.

With these and other objects in view there has been illustrated on the accompanying drawings one form in which the invention may be conveniently embodied in practice.

In the drawings:

Fig. 1 represents a perspective view of the humidifying apparatus with the door in open position and having certain parts broken away to show the interior construction.

Fig. 2 is an enlarged fragmentary sectional view of one of the humidifier units showing the overflow valve in closed position.

Fig. 3 is an end view of the same.

Fig. 4 is a fragmentary front elevation of the humidifying apparatus.

Fig. 5 is a transverse sectional view of the

same, taken along the line 5—5 of Fig. 3, looking in the direction of the arrows.

Referring now to the drawings in which like reference numerals denote corresponding parts throughout the several views, the numeral 10 indicates generally an enclosing cabinet supported upon four pedestal feet 11 and provided with a removable top cover lid 12.

In order to gain access to the interior of the cabinet from the front, provision is made of a laterally swinging hinged door 13 located intermediate a lower channel bar 14 and an upper ornamental grille 14a through which the humidified air is adapted to flow out into the room.

Both the radiator and humidifier sections of the apparatus are adapted to be connected at their ends to an inlet header 15 and an outlet header 16, each of said headers having an outwardly extending tapped boss 17 (18) at its lower end for connecting said headers to an inlet pipe 19 and an outlet pipe 20, respectively.

The radiator section comprises a plurality of tiers (two in this instance) of horizontal copper tubes 21. Each tier comprises three tubes. All six of the radiator tubes are surrounded by a plurality of uniformly spaced parallel copper radiating fins 21a, preferably soldered to said tubes.

Provision is made of a plurality of humidifying units, three in this instance, each of which comprises a horizontal copper water pan 22 supported by three parallel tubes 23, similar to the tubes 21 of the radiator section. All of said tubes 21 and 23 are suitably sealed into the headers 15 and 16 by means of compression coupling screws 24, which connect said tubes to a plurality of vertically spaced hollow bosses 25 extending inwardly from said headers.

The humidifier tubes 23 are adapted to be positioned adjacent the bottoms of the water pans 22 and are passed through the end walls 26 and 27 thereof, being suitably sealed in said walls, as by welding. The water for humidifying the heated air is supplied to the radiator cabinet 10 by means of a small vertical feed pipe 28 preferably of copper tubing 100

and terminating at its upper end in a down-turned U-shaped loop 29 adapted to be closed by a pet-cock 30. By suitably adjusting the pet cock 30, a continuous supply of water 5 may be fed into the upper pan 22.

The vertical feed pipe 28 is held in a rigid position by means of a pair of eye-brackets 28a and 28b embracing said feed pipe 28 and being attached to an end wall of the inlet 10 header 15.

Each of the two uppermost water pans 22 has a short overflow pipe 31 passing down through a depressed well 32 located at an 15 intermediate position in the bottom of said pans 22. Each of the overflow pipes 31 has its upper end beveled at 33 in order to permit the water to overflow at a rate in direct proportion to the level of the water above the top of said overflow. The lowermost water 20 pan 22 is provided with a long overflow pipe 34 which permits the water in said pan to be carried off to any suitable drainage device, such as a sink, not shown, located at some lower point. The overflow pipe 34 is surrounded by a depressed well 35 similar to the wells 32 mentioned above.

Each of the overflow pipes 31 and 34 is provided with a side orifice 36, the lower edge 30 of which is flush with the bottom of the wells 32 and 35, thus insuring a complete drainage from the humidifying pans 22 when the orifices 36 are opened. Each of the orifices 36 is adapted to be selectively closed by means of a concave valve cup 37 formed 35 upon the lower end of a hand-operated lever 38 pivoted to the upper end of the valve pipes 31 and 34 by a rivet 39, as clearly shown in Figs. 2 and 3.

By means of this construction it will be 40 understood that if it is found that the three pans 22 are supplying an excessive amount of humidity to the atmosphere, the humidifying effect may be reduced one-third by merely swinging the valve lever 38 of the top pan to a horizontal position and thus opening the orifice 36 in the upper overflow pipe 31. The upper pan will thus be thrown out of action 45 as a humidifying unit. The middle and bottom humidifying pans may also be rendered inactive in a similar manner if desired. This construction also permits the pans to be readily cleaned and flushed whenever desired.

As a means for supporting the combined 50 radiator and humidifying units, the end walls of the cabinet 10 are provided with a pair of horizontal angle brackets 40 and 41, upon which the inlet header 15 and the outlet header 16 are adapted to rest respectively, said headers being secured to said brackets 55 as by screws 42.

In order to produce the maximum humidifying action, the pans 22 are preferably disposed in staggered relationship relative to each other, thus causing the heated air from 60 the radiator section below to flow horizontally

back and forth over the humidifying pans and absorb the maximum amount of water vapor therefrom. The stream of moistened air will then be caused to flow upwardly, where it will be diverted forwardly at the top 70 of the cabinet 10 and out through the grille 14a by means of a pair of curved baffle plates 43 and 44. The direction of the hot air currents in the apparatus is indicated by the arrows, as shown in Fig. 5. 75

Operation

To operate the combined radiator and humidifier, the pet-cock 30 will first be opened for filling the three pans 22 with water. 80 The pet-cock 30 will then be adjusted to allow a stream of water to flow into the upper pan 22, the amount of said stream preferably being slightly in excess of that required to compensate for the moisture evaporated in 85 the pans 22. The heating medium will then be introduced into the inlet header, causing the tubes 21 and 23, and the radiator fins 21a and the water in the humidifier pans 22 to rapidly become heated. 90

This hot air current rising from the radiator section will then be caused to flow in a sinuous path between the staggered pans 22 and will rapidly absorb the heated water vapor rising from the pans 22. The humidified hot air will then flow upwardly and outwardly into the room through the grille 14a. 95

While there has been disclosed in this specification one form in which the invention may be embodied, it is to be understood that this form is shown for the purpose of illustration only, and that the invention is not to be limited to the specific disclosure but may be modified and embodied in various other forms without departing from its spirit. In 100 short, the invention includes all the modifications and embodiments coming within the scope of the following claims. 105

Having thus fully described the invention what is claimed as new and for which it 110 is desired to secure Letters Patent is:

1. In a humidifier for the air in a room, a cabinet adapted to rest upon the floor of said room, said cabinet having top and bottom openings, a pair of inlet and outlet headers supported by the end walls of said cabinet, a plurality of tiers of horizontal tubes connecting said headers, the lower tiers of tubes being provided with fins and comprising a radiator section, the upper tiers being immersed in a plurality of water pans and comprising humidifying units, means for supplying heating fluid to said inlet header, the heated air from said radiator section being caused to absorb the moisture rising from 115 the humidifying units. 120

2. In a humidifier for the air in a room, a pair of inlet and outlet headers, said headers being connected by a plurality of rows of horizontal tubes, a water pan for sur- 130

- rounding one of said upper rows of tubes, means for supplying heating fluid to said inlet header, the heated air rising from the lower tubes being humidified by the water vapor rising from said water pan.
3. In a humidifier for the air in a room, a pair of inlet and outlet headers, said headers being connected by a plurality of horizontal tubes, a water pan for surrounding one of said upper tubes, means for supplying heating fluid to said inlet header, the heated air rising from the lower tubes being humidified by the water vapor rising from said water pan.
- 10 4. In a humidifier for the air in a room, a pair of vertical inlet and outlet headers, means for supplying a heating fluid to said inlet header, said headers being connected by a plurality of rows of horizontal tubes, the bottom rows of tubes being surrounded by fins and comprising a radiator section, each of the upper rows of tubes being immersed in a horizontal water pan open at the top, means for supplying water to the upper pan, and means for causing water to overflow from said upper pan into the pans beneath, and an overflow drain in said lowest pan.
- 20 5. In a humidifier for the air in a room, a plurality of horizontal rows of heated tubes, one of said upper rows of tubes being immersed in a water pan, and means for causing the heated air from the rows of tubes below said pan to pass over the surface of the water in said pan to absorb water vapor therefrom.
- 25 6. In a humidifier for the air in a room, a plurality of horizontal rows of heated tubes, one of said upper rows of tubes being immersed in a water pan, means for causing the heated air from the rows of tubes below said pan to pass over the surface of the water in said pan to absorb water vapor therefrom, and an overflow pipe extending downwardly through said pan, said overflow pipe being located in a depressed well in the bottom of said pan.
- 30 7. In a humidifier for the air in a room, a plurality of horizontal rows of heated tubes, one of said upper rows of tubes being immersed in a water pan, and means for causing the heated air from the rows of tubes below said pan to pass over the surface of the water in said pan to absorb water vapor therefrom, and an overflow pipe extending downwardly through said pan, said overflow pipe having a beveled open upper end whereby the rate of overflow will be proportional to the level of the water above the bottom of the beveled top opening in said pipe.
- 35 8. In a humidifier for the air in a room, a horizontal water pan, means to heat the water therein, an overflow pipe extending downwardly through said pan and having an open upper end, said pipe having a side orifice above the bottom of said pan, and a lever pivoted to said pipe and having a valve cap adapted to fit said orifice.
- 40 9. In a humidifier for the air in a room, a horizontal water pan, means to heat the water therein, an overflow pipe extending downwardly through said pan and having an open upper end, said pipe having a side orifice above the bottom of said pan, and a lever pivoted to said pipe and having a valve cap adapted to fit said orifice, said orifice being closed when said lever is in a vertical position.
- 45 In testimony whereof, we have affixed our signatures to this specification.
